Specification for Design.

Patented Nov. 29, 1921.

Application filed July 16, 1921. Serial No. 485,306. Term of patent 14 years.

To all whom it may concern:

Be it known that we, ALFRED L. EVENDEN, JAMES D. CASEY, and JOSEPH A. CASEY, citizens of the United States, and residents of Rome, in the county of Oneida and State of New York, have jointly invented a new, original, and ornamental design for Pincers, of which the following is a specification, reference being had to the accompanying drawing, forming part thereof.

Figure 1 is a perspective view of our new design for pincers.

Fig. 2 is an elevation showing the opposite side of the pincers represented in Fig. 1.

The pincers shown in the drawing are substantially a reproduction of the pincers shown and described in our application for

patent for improvements in implement for fixing tips to laces, filed March 28, 1921, and bearing Serial Number 456,373.

We claim, and desire to secure by Letters Patent, the following:

The ornamental design for pincers, as shown.

In testimony whereof we have signed our names to this specification in the presence of two subscribing witnesses.

ALFRED L. EVENDEN.
JAMES D. CASEY.
JOSEPH A. CASEY.
